UNITED STATES PATENT OFFICE,

JOSEPH KLINGER, OF CLEVELAND, OHIO.

BALLOT-BOX.

SPECIFICATION forming part of Letters Patent No. 295,560, dated March 25, 1884.

Application filed January 24, 1884. (No model.)

To all whom it may concern:

Be it known that I, JOSEPH KLINGER, of Cleveland, in the county of Cuyahoga and State of Ohio, have invented certain new and useful 5 Improvements in Ballot-Boxes, of which the following is a specification. . . .

This invention relates to ballot-boxes in which white and black balls are used in voting; and it consists of a convenient-sized box provided with two cylindrical chambers having spiral passage-ways downward through them, in which the balls are placed, and from the bottom of which one ball at a time is ejected and deposited into a drawer or compartment provided for that purpose in the bottom of the aforesaid box. The balls are ejected and deposited, as stated, by means of a mechanism consisting of two gates covering the mouths of the discharge-openings of the said spiral chambers, connected by rods attached to a tilting lever in such a manner that but one of the said gates can be operated at a time, and but one ball ejected and deposited at one time. The said mechanism also operates a registering device to show the number of balls deposited, and also operates a bell-signaling device simultaneously with the aforesaid balloting mechanism. The said mechanisms are constructed, combined, and operate as hereinafter 30 fully described and claimed.

In the accompanying drawings, Figure 1 is a perspective view of my new ballot-box. Fig. 2 is a vertical section in line xx of Fig. 3. Fig. 3 is a vertical section in line yy of Fig. 2. 35 A is a box, suitably made of wood, in the lower portion of which is provided a drawer having two compartments, comprising the receptacle for the ballots or balls, as hereinafter shown, said drawer being shut off from the upper portion of the box by a floor or partition, a . The upper portion of said box has an offset covered by an arch, B, forming an open chamber, in which is located the knobs and a balanced lever, E, connected together by brackets, 40 to be operated by the hand of the operator in casting a ballot. The internal mechanism operated by these knobs will be described further on. Within the box are made and placed two cylinders, C C, each having a spiral groove 45 for holding the balls. The lower end of each

cylinder is provided with a spout, c , leading toward the front side of the box, and the mouths of said spouts are closed by sliding gates D D', connected to and operated by the said knobs. The balanced lever E is pivoted to the front 55 of the box, underneath the arch B, and from its ends are suspended two brackets, F F'. These brackets are L-shaped, and to their outer ends are suspended push-rods $f f$, to the upper ends of which are attached the said knobs $k k$, and to the lower ends of said rods $f f$ are attached the aforesaid gates D D'. Beneath the floor of the arched chamber is placed a lever, M, which plays in a slotted frame, N, held up and supported therein by a pin, p , secured at the middle part and passed through the lower bar of said frame N. Said pin is surrounded by a spiral spring, s , the tension of which keeps the lever up, but will allow it to be depressed. To the said lever are attached two standing rods, $r r$, passing up through the floor, like the rods $f f$ to the brackets F F'. Through the floor a are made two holes, near the mouths of the spouts, through which the balls are deposited, one by one, into 65 the receptacle below. A spring-trap, T, closes said openings and is pressed down by the gates whenever they are forced down, thus letting the one ball drop which is in front of the gate. The gates, as seen in Fig. 3, have their lower 70 ends cut out large enough to let one ball pass through at once. There is also only space enough between the gate and the front wall of the box for one ball at a time to occupy it, the gate shutting off egress of balls until it is 75 again raised.

At each side of the box is a registering device inclosed in a hinged cover, U. The register consists of a numbered ribbon wound on spools journaled in side brackets, u , the upper 80 spool having a ratchet wheel, u' , which is operated by a dog, v , on each end of the lever M. A spring, v' , holds the ratchet-wheel from turning backward. To the lever M is also attached an arm, W, which is bent upward and slides in 85 sockets W^2 , attached to the inside of front wall of box A. A bell-hammer, z , is pivoted to inside wall of box A, above said sliding rod W, having a short arm, y , caught by a spring-catch, y^2 , attached to said sliding rod W. The move- 90 95 100

ments of the lever M operate the said hammer, which strikes the bell on the top of the arch every time said lever is depressed, thus giving a signal, by ringing the bell, simultaneously with each ball dropped. A spring, s^2 , throws the hammer against the bell as the said catch y^2 slips off the arm y . In one of the cylinders C are contained white balls and in the other black balls.

10 From the foregoing description the operations of this device will be seen to be as follows: The box being presented to the voter, he places his finger on one of the knobs with in the arch and presses down thereon, when 15 one ball is deposited in the receptacle below by the downward movement of the gate, and the lever M is also pressed down at the same time and at the same side, moving the register one notch, and at the same time causing 20 the hammer to strike the bell.

It will be observed that both knobs cannot be forced down at the same time, by reason of the balanced lever E preventing. Therefore 25 a ball from both sides cannot possibly be dropped at the same time.

A hinged lid is provided to the top of the box A, for the purpose of replacing the balls in the cylinders after the balloting is over. This may be done by taking out the drawer 30 and pouring the balls into the top of each cylinder, as they belong.

Having described my invention, I claim—

1. In a ballot-box, the combination, with the two cylinders C C, having spiral chambers ter-

minating with discharge-spouts $c c$, of the 35 mechanism constructed and arranged to eject and deposit one ball at a time, and the mechanism constructed and arranged to operate the register, and a mechanism constructed and arranged to operate the bell-signal simultaneously, as described.

2. The pivoted balance-lever E, brackets F F', supporting the rods $f f$, provided with the knobs $k k$, and carrying the gates D D', in combination with the spouts $c c$ of said cylinders 40 C C, and the traps T T, operating to eject and deposit the balls, substantially in the manner and for the purpose specified.

3. The combination, with the balance-lever E, brackets F F', and rods $f f$, provided with 50 knobs $k k$, and carrying gates D D', of the lever M, hung in the slotted frame N, and provided with pin p and spring s , and the dog v , for operating the registering device, substantially as and for the purpose specified.

4. The combination, with the balance-lever E, brackets F F', and rods $f f$, provided with knobs $k k$, of the lever M, hung in the slotted frame N, and provided with pin p and springs s , and the arm W, sliding in sockets W^2 , and provided with spring-catch y^2 , operating the bell-hammer z , for sounding the bell-signal, substantially as and for the purpose specified.

JOSEPH KLINGER.
